[57] **CLAIM**

The ornamental design for a clippings catcher for overlock sewing machines, as shown and described.

DESCRIPTION

FIG. 1 is a top plan view of a clippings catcher for overlock sewing machines showing my new design;
FIG. 2 is a bottom plan view thereof;

FIG. 3 is a front elevational view thereof, the rear view being a mirror image;

FIG. 4 is a right side elevational view thereof, the left side being a mirror image; and

FIG. 5 is a top perspective view thereof.
The crosshatching shown in FIGS. 1-5 is understood to repeat throughout the indicated area.

FIG. 1

FIG. 4

FIG. 2

FIG. 3
